UNITED STATES PATENT OFFICE.

CHRISTIAN Y. ROOP, OF KANSAS CITY, MISSOURI.

OIL-BURNER.

No. 926,137.

Specification of Letters Patent.

Patented June 29, 1909.

Application filed November 10, 1908. Serial No. 461,975.

To all whom it may concern:

Be it known that I, CHRISTIAN Y. ROOP, a citizen of the United States, residing at Kansas City, in the county of Jackson and

5 State of Missouri, have invented certain new and useful Improvements in Oil-Burners, of which the following is a specification.

This invention relates to oil burners and my object is to produce a burner with which 10 crude oil or distillates may be employed as fuel.

A further object is to produce an oil burner embodying the desirable features of simplicity, strength, durability and cheapness of construction.

With these objects in view, the invention consists in certain novel and peculiar features of construction and organization as hereinafter described and claimed; and in 20 order that it may be fully understood reference is to be had to the accompanying drawing, in which;

Figure 1, is a plan view of a burner embodying my invention, one half of the hood 25 being omitted. Fig. 2, is a central vertical section of the burner. Fig. 3, is a plan view of the central portion of the lower part of the burner. Fig. 4, is an inverted plan view of a part of the hood of the burner. Fig. 5, is a perspective view of the upper end of the oil-supply or feed pipe.

In the said drawing where like reference characters identify corresponding parts, 1 indicates a pan preferably circular and of 35 cast metal and provided with a plurality of air-inlet openings arranged in circular series and surrounded by the upwardly projecting walls 3. A circular wall 4 of less height than the walls 3, also projects upward from the bottom of the pan and is disposed within and concentrically of the circular series of walls 3, and rising from the bottom of the pan centrally of wall 4 and to be a greater height than walls 3, is a 40 hollow column 5 provided in its upper end or top with a preferably threaded hole 6, and in the upper side of said top with preferably radial grooves or channels 7.

50 8 is an oil-supply or feed pipe extending up through the hollow column and of less diameter than the hollow of said column channel so as to provide an air space 9, which is open to the atmosphere at its lower end. The pipe 8 is externally threaded at 55 its upper end by preference and engages the threaded hole 6 in the top of the column,

and preferably projects some distance above the latter with its projecting portion formed with openings which preferably are in the form of radial kerfs 10.

60 The hood preferably consists of a plurality of radially-arranged downwardly-opening elbow portions 11 which externally embrace and rest upon the circular walls 3. The upper ends of the passages of said elbow 65 portions communicate at their inner ends with a circular chamber 12 receiving the upper portion of the column and of a materially greater diameter than the latter, and said chamber 12 is extended upwardly by 70 preference by the dome 13 of the hood. The chamber 12 is preferably deepened by the provision of a wall 14 depending at the inner ends of the passages of the elbow portions 11, it being noted in this connection that the 75 lower edge of wall 14 terminates in a plane above the lower ends of the elbows, as shown clearly in Fig. 2, and that the lower ends of the elbows are spaced some distance above the bottom of the pan.

80 The construction as described is that which is preferred when crude oil is employed as a fuel. When distillates are employed as a fuel the column is preferably surmounted by a cap consisting of a cylindrical portion 15 85 surrounding and spaced from the upper end of the column and a substantially truncated cone-shaped upper portion 16. The lower portion of the conical portion rests upon the upper end of the column, and the upper 90 end of the oil-supply or feed pipe engages the tapering portion near its upper end to aid in holding the cap centrally with respect to the column, it being further noted that the upper end of said pipe terminates short 95 of the top of the cap so as to provide the intervening chamber wherein distillation of the more volatile oils may occur.

100 The hood is preferably provided with a perforated lug 18 for convenience in removing it from or placing it upon the burner while hot by means of a poker or similar device.

105 The pan is adapted to be fitted in opening 19 of a plate 20, which plate forms the partition of a fire-box not shown, so that the draft up through said box must pass up through the inlet openings 2, the elbow portions 11, chamber 12, and then downward and outward in order to escape from the pan.

110 The burner can be raised to vaporizing temperature in any suitable manner, for in-

stance, by pouring a suitable quantity of kerosene into the pan and igniting it. After the burner has attained the desired temperature, the oil is permitted to flow up 5 through pipe 8, such oil being a distillate by preference, if the burner is equipped with the cap described. In the passage of the oil up through pipe 8, it does not attain a volatilizing temperature until it reaches 10 the upper end of the column, as the air space 9 of the column insulates the pipe below its point of physical contact with the column. As the oil thus reaches the top of the column and is vaporized it passes outward in all 15 directions through the openings 10 except a small volume which fills chamber 17 of the cap and thus forms a reservoir which tends to insure an even and uninterrupted pressure of the vapor through the grooves 7 and 20 down through the space between the upper end of the column and the lower portion 15 of the cap. As the vapor escapes from the lower end of the cap it mixes with the air entering chamber 12 from the elbow portions 25 so as to form a combustible compound or mixture; it being understood that when it mixes with the vapor it is at a high temperature because of its passage through the elbow portions which, when the burner is in 30 operation, are highly heated. The mixture begins to burn immediately and the flame impinges on the bottom of the pan around the column and flares radially outward against and between the walls 3 and of 35 course, the elbow-portion 11. If the supply of oil is sufficient the flame will completely envelop all of the burner except the bottom and outer surface of the pan, and may extend several feet upward. It may be turned 40 sufficiently low to simply disclose a white flame between the radially-arranged elbows.

When it is desired to employ crude oil as fuel, the cap is omitted. In this case the crude oil, after it attains the top of the 45 column, flows outwardly through the grooves 7 and then downward on the column, the lighter oils being vaporized at the top of the column and passing downward as vapor outward of the column, and the heavy oils 50 flowing downward upon the latter, this vapor mixing with the hot air supplied by the elbows and filling the lower central portion of the burner with a flame which impinges on the heavy oils on the column and on the 55 bottom of the pan within wall 4. This blast of flame upon such heavy oils in the bottom tends to coke such oils and then burns the coke and this action continues as long as the burner is in operation.

60 From the above description it will be apparent that I have produced a burner embodying the features of advantage enumerated as desirable and susceptible of modification as regards its form, proportion, construction and organization without depart-

ing from the spirit and scope of the appended claims.

Having thus described the invention, what I claim as new and desire to secure by Letters Patent is:

1. An oil burner comprising a pan provided with an opening and with a hollow column communicating at its lower end with the atmosphere and provided with channels in its upper end extending to its 75 outer margin, a hood over the column and depending to a plane between the upper and lower ends of the same and provided with a tubular elbow portion establishing communication between the interior of the hood 80 and the said opening of the pan; a cap consisting of a lower portion surrounding and spaced from the upper part of the column and an upper portion tapering upwardly from the lower portion and overhanging 85 and resting upon the column and bridging the channels thereof, and an oil-supply pipe extending up through the column and projecting above the same into the upper portion of the cap and, below the upper end of 90 the column, of smaller diameter than the interior or hollow portion of the same.

2. An oil burner comprising a pan provided with a hollow column communicating with the atmosphere at its lower end and 95 provided also with an opening, and provided furthermore with a wall surrounding the column and projecting upward from the bottom of the pan, and a hood fitting over and surrounding the upper part of the 100 column and provided with an elbow portion communicating at its lower end with the opening of the pan and at its upper end with the interior of the hood; said hood being provided inward of the lower end of 105 the elbow with an annular wall terminating above the wall projecting upwardly from the bottom of the pan, and a cap within the hood surrounding the upper end of the column and spaced from the latter.

3. An oil burner, comprising a pan provided with openings arranged in circular series and with upwardly projecting walls surrounding such openings, and provided also with a centrally-arranged hollow column which communicates at its lower end with the atmosphere, and provided furthermore with an annular wall surrounding the column within the circle described by said 115 openings and terminating short of the upper ends of the walls of the latter; a hood fitting over the upper end of the column and provided with radially-arranged elbow portions fitting at their lower ends upon the walls of said openings and having passages communicating at their lower ends with said openings and at their upper ends with the interior of the hood, and provided below the inner ends of said elbow portions 120 with a depending wall; and a cap within 125

130

the hood comprising a lower portion surrounding and spaced from the upper portion of the column.

4. An oil burner comprising a pan provided with openings arranged in circular series and with upwardly-projecting walls surrounding such openings, and provided also with a centrally-arranged hollow column which communicates at its lower end with the atmosphere, and is equipped with radial grooves in the upper side of its top; said pan being also provided with an annular wall projecting upward from the bottom around the column within the circular series of openings; a hood fitting over the column and provided with a series of radial tubular elbow portions resting at their lower ends upon the walls of said openings, and establishing communication between the said

openings of the pan and the interior of the 20 hood; an oil-supply pipe extending up through the hollow column and spaced from the inner side of the latter and secured to and projecting above the top of the column, and provided above the latter with 25 openings; and a cap comprising an upwardly-projecting portion resting upon the top of the column and surrounding the upper end of the pipe, and a lower portion surrounding and spaced from the upper end 30 of the column.

In testimony whereof I affix my signature, in the presence of two witnesses.
